drawings illustrating the best mode of carrying out the invention. The drawings are given in the order indicated in the claims and are numbered 1 through 7. The drawings are as follows:

UNITED STATES PATENT OFFICE

COILING MACHINE

Carl O. Kirchner, Carthage, Mo., assignor to
Leggett & Platt, Inc., Carthage, Mo.

Application December 5, 1949, Serial No. 131,105

7 Claims. (Cl. 153—65)

1

This invention relates to improvements in a spring coiling machine.

The main objects of this invention are:

First, to provide an arborless coiling machine in which the diameter and pitch of the work can be varied throughout a substantial range and both accurately controlled.

Second, to provide a coiling machine having these advantages in which the tools or forming members are of simple form and easily adjusted to produce work of the desired character and adjusted to compensate for wear.

Third, to provide a coiling machine which when set to produce coiled material of the desired dimensions and pitch is automatic in operation and requires little attention on the part of the operator.

Objects relating to details and economies of the invention will appear from the description to follow. The invention is pointed out in the claims.

A preferred embodiment of the invention is illustrated in the accompanying drawings, in which:

Fig. 1 is a side elevational view of a coiling machine embodying my invention, only fragments of the frame and feed rolls of the machine being illustrated and these being shown mainly conventionally.

Fig. 2 is a fragmentary view looking from the top of Fig. 1.

Fig. 3 is a fragmentary view mainly in section on a line corresponding to line 3—3 of Fig. 1.

Fig. 4 is a fragmentary view mainly in section on a line corresponding to line 4—4 of Fig. 1.

Fig. 5 is a fragmentary view partially in section on a line corresponding to line 5—5 of Fig. 1.

Fig. 6 is an end view of one of the faces of one of the forming tools.

Fig. 7 is a fragmentary view of the face end of another of the forming tools.

In the accompanying drawing 1 represents the bed or frame of the machine, 2—2 feeding rolls for the wire stock 3. The head member 4 on which the forming tools are mounted is desirably in the form of a plate-like block secured to the frame 1 by means of screws 5.

In the embodiment illustrated I provide a plurality of forming tools 6, 7, 8 and 9 arranged in series to successively act on the work as it is forced through the tubular guide 10 into successive impinging engagement therewith. The tools 6, 7 and 8 are arranged in a generally radial angularly spaced relation relative to each other and to the work while the tool 9 is arranged in a generally tangential relation to the work indicated at

11 (see Figs. 1 and 4). The tools 6, 7 and 8 have grooved end faces, the grooves having some pitch as is indicated at 12 in Fig. 6. The face 13 of the tool 9 faces laterally and inwardly.

5 The holders for the tools 6, 7 and 8 are desirably alike and a description of one will suffice for all of them. The holder comprises a slot-like generally radially disposed recess 14 formed in the head member and of a width to receive and laterally support the tool as is shown in Fig. 1. The recess is of such depth as to permit the tilting of the tool therein as is illustrated in the drawing, the tool being tiltably supported intermediate its ends by means of the rest 15. The top plate 16 is removably secured to the head member by means of screws 17 and overhangs the recess. The top plate carries the adjusting screws 18 engaging the tool on opposite sides of the rest 15 so that by adjusting these screws the tool may be adjusted to proper position to produce work of the desired pitch.

20 The tools are preferably provided with hardened face portions 19 as conventionally indicated in Fig. 5. The threaded end thrust sustaining or abutment member 20 engages the end of the tool and is adjusted to properly position the tool to produce work of the desired diameter and to compensate for wear on the tool. The lock nut 21 secures the abutment in its adjusted position.

25 The recess 22 for the tool 9 is of such dimensions as to permit both axial and radial tilting of the tool. This tool is supported for axial tilting adjustment by the rest 23 at the bottom of the recess 22, the tool being adjusted and secured in its adjusted position by the setscrews 24 engaging the tool at opposite sides of its rest 23 and carried by the top plate 25 which is detachably secured to the head member by the screws 26.

30 The tool 9 may be tiltably adjusted on its rest 29 for radial adjustment by means of the screws 30. It will be noted that the inner end of the tool 9 in the embodiment illustrated is quite close to and in overlapping relation to the inner end of the guide tube 10. With this arrangement of parts the wire stock 3 is fed through the guide 10, the inner end of which is closely adjacent to the first tool 6 of the series and across the face thereof and successively into impinging relation to the other tools of the series. All of the tools are set to produce work of the desired diameter and pitch and also to compensate to a substantial degree for the character of the stock. While the coils are given an effective set through engagement with the several coiling members or tools some stock is of such character that it springs back to some extent.

While I desirably employ the series of four tools illustrated, a lesser number of the end thrust series may be used being angularly positioned relative to the work in proper relation to the guide tube so that it delivers the stock in impinging relation to the first tool without such open space to permit outward buckling of the stock between the guide tube and the first tool. In starting the machine the stock is advanced through the guide tube and ordinarily by means of a hand tool is guided into proper relation or engagement with the first former tool. The former tools being properly adjusted either before or after making a test coil the machine is entirely automatic until it is necessary to start a new bail of stock or to readjust the machine for wear or variation in the diameter and pitch of the coil desired.

I have illustrated and described my invention in a highly desirable embodiment thereof. I have not attempted to illustrate or describe certain embodiments or adaptations which I contemplate as it is believed that this disclosure will enable those skilled in the art to embody or adapt my invention as may be desired.

Having thus described my invention, what I claim as new and desire to secure by Letters Patent is:

1. In a spring coiling machine, the combination with a support, of a plurality of forming tools provided with grooved end faces and disposed in generally radial angularly spaced relation to the work, said support being provided with individual holders for said tools, each holder including a rest tiltably supporting the tool intermediate its ends, adjusting screws engaging the tool on opposite sides of the rest for tiltably adjusting the tool axially of the work and clamping it in its adjusted position, an adjustable end thrust abutment for the outer end of the tool, a tubular guide disposed with its inner end closely adjacent the first tool of the series and positioned to guide the stock into the groove and against the face of such tool.

2. In a spring coiling machine, the combination with a head member, of a forming tool provided with a grooved end face and disposed in a generally radial relation to the work, said head member being provided with a holder for said tool comprising a groove-like generally radial recess of a width to receive and provide side support for the tool, a rest at the bottom of the recess tiltably supporting the tool intermediate its ends, a removable top plate, adjusting screws carried by said top plate and engaging the tool on opposite sides of the rest for tiltably adjusting the tool axially of the work and clamping it in its adjusted position, an adjustable end thrust abutment for the outer end of the tool.

3. In a spring coiling machine, the combination with a head member, a tool disposed in generally tangential relation to the work and having a laterally and inwardly facing grooved face at its inner end, a holder for such tool comprising a recess in said head member of such dimensions as to permit tilting adjustment of the tool radially and axially of the work, a removable top plate for said recess, a rest at the bottom of the recess for tiltably supporting the tool for adjustment axially of the work, screws carried by said top plate and engaging the tool on opposite sides of said rest for axially adjusting and clamping the tool in adjusted axial position, a rest at the inner side of said recess for tiltably supporting said tool for adjustment

radially of the work, and screws disposed through the outer wall of the recess engaging the tool on opposite sides of said rest for radially adjusting and clamping said tool in its adjusted position.

4. In a spring coiling machine, the combination with a support, of a plurality of forming tools disposed in generally radial angularly spaced relation to the work and provided with grooved end faces, means on said support for individually adjusting said tools for axial and radial adjustment relative to the work, a bar-like tool disposed in succeeding relation to the aforesaid tools and in generally tangential relation to the work, said tool having a laterally and inwardly facing grooved face at its inner end, said grooved face extending generally lengthwise the tool, and a holder for such tool provided with means for adjusting its work engaging face axially and radially relative to the work whereby the tools may be adjusted to produce helically coiled springs of different diameters and pitch, said last named means including a recess in said holder for receiving said bar-like tool, a rest at the bottom of said recess for tiltably supporting the bar-like tool between its ends, and adjustable means on said holder for engaging the bar-like tool for tiltably adjusting the same on said rest in a direction axially of the work and for clamping it in adjusted position.

5. In a spring coiling machine, the combination with a support, of a radially disposed tool provided with a grooved end face, a holder for said tool provided with means for adjusting the tool radially and supporting it in its adjusted position and for adjusting it axially and supporting it in its adjusted position, a bar-like tool disposed in succeeding relation to the aforesaid tool and in generally tangential relation to the work and having a laterally and inwardly facing grooved face, said grooved face extending generally lengthwise the tool, means for adjustably supporting said tool axially of the work, and further means for adjustably supporting said tool radially of the work, said means for adjusting the bar-like tool axially of the work including a holder having a recess therein for receiving said bar-like tool, a rest at the bottom of the recess for tiltably supporting said bar-like tool in said recess, and adjusting means on said holder for engaging said bar-like tool and tilting the same on said rest in a direction axially of the work and for clamping it in adjusted position.

6. In a spring coiling machine, the combination with a support, of a bar-like tool disposed in generally tangential relation to the work and having a laterally and inwardly facing grooved face, said grooved face extending generally lengthwise the tool, means for adjustably supporting said tool axially of the work, and further means for adjustably supporting said tool radially of the work, said means for adjusting the bar-like tool axially of the work including a holder having a recess therein for receiving said bar-like tool, a rest at the bottom of the recess for tiltably supporting said bar-like tool in said recess, and adjusting means on said holder for engaging said bar-like tool and tilting the same on said rest in a direction axially of the work and for clamping it in adjusted position.

7. In a spring coiling machine, the combination of a head member, of a bar-like tool provided with a grooved coil engaging face, said

head member being provided with a holder for said tool comprising a groove-like recess of a width to receive and provide a support for the tool, a rest at the bottom of the recess tiltably supporting the tool intermediate its ends, a removable top plate opposite from said rest for retaining said tool in said recess, and adjusting screws carried by said top plate and engaging the tool on the opposite sides of the rest for tiltably adjusting the tool axially of the work and 10 clamping it in adjusted position.

CARL O. KIRCHNER.
